UNITED STATES PATENT OFFICE

125,367

DESIGN FOR A DRESS ENSEMBLE OR SIMILAR ARTICLE

Ann Florek, Chicago, Ill.

Application September 21, 1940, Serial No. 95,246

Term of patent 3½ years

To the Commissioner of Patents:

Be it known that I, Ann Florek, a citizen of the United States, residing at 2317 N. Kimball Ave., Chicago, in the county of Cook and State of Illinois, have invented a new, original, and ornamental Design for a Dress Ensemble or Similar Article, of which the following is specification, reference being had to the accompanying drawing, forming part thereof.

The pockets of the jacket member and the blouse section of the dress member of the ensemble are sequin trimmed, as shown.

I claim:

The ornamental design for a dress ensemble or similar article, substantially as shown and described.

ANN FLOREK.
